METAL WORKING APPARATUS

Ernest J. Svenson, Rockford, Ill., assignor, by mesne assignments, of one-half to W. F. and John Barnes Company, Rockford, Ill., a corporation of Illinois, and one-half to Odia Corporation, Rockford, Ill., a corporation of Illinois

Filed Feb. 27, 1959, Ser. No. 796,097
23 Claims. (Cl. 77—33.5)

The present invention relates to machine tools and more particularly to self-contained machine tool units and controls.

Many worth-while advantages are gained by using hydraulic systems in machine tools, particularly in self-contained machine tool units, to control and to power movements which operate machine tools in relation to workpieces. For this reason, much effort and ingenuity have gone into the development of hydraulic control and power systems for self-contained machine tool units that are advanced and retracted in relation to a workpiece by a hydraulic motor controlled by hydraulic control structure incorporated into the hydraulic power system which includes the hydraulic motor.

However, the use of hydraulic control and power systems in this environment has pointed up a number of problems which have not been previously overcome on an altogether satisfactory basis. One such problem has been that of progressive heating of the hydraulic fluid during use of the machines. Increasing temperature of the hydraulic fluid not only changes the viscosity of the fluid, upsetting operation of the hydraulic system, but it also changes the temperature of major components of the machine structure and in this manner affects the positional relationships of fundamental machine parts. Some of the effects and results of heating of the hydraulic fluid in machine tools of this character include the following:

(1) Variation in the speed at which cutting tools are moved relative to a workpiece,

(2) Changes in the alignment of cutting tools relative to workpieces,

(3) The causation of bending actions between cutting tools and workpieces resulting in scoring and breaking down of structural parts, and

(4) Numerous difficulties arising from an undue reduction of the viscosity of the fluid, such, for example, as fluid leakage with the necessity for replenishing the hydraulic fluid supply, fire hazards, and a general contamination of the environment creating hazards to the operating personnel and requiring increased care and maintenance of the machinery.

Prior efforts to minimize the effect of progressively increasing hydraulic fluid temperatures attending the operation of machines equipped with such hydraulic systems have included the practice of operating a machine an hour or more before it is actually put into use in order to obtain some semblance of a stabilized temperature level. This expedient is not only expensive but is by no means wholly effective since the fluid temperature still changes after production is started. Other attempts have been made to provide means for compensating for changes in the viscosity of the fluid incident to changes in the fluid temperature. However, such approaches have lacked much to be desired in that they only partially compensate for the effects of temperature variation and do not eliminate temperature increases or many undesirable effects of temperature increases.

As a matter of fact, the problems associated with the use of hydraulic control and actuating systems in machine tools have been so serious as to lead some manufacturers to abandon the use of such systems, at the sacri-

2

fice of their advantages, and go back to the use of mechanical drives.

One object of my invention is to provide an improved machine tool with an improved hydraulic control and actuating system which will operate with great efficiency and effectiveness without significantly heating the hydraulic fluid used in the system, thereby eliminating the difficulties and problems previously associated with progressively increasing fluid temperatures in this environment.

Another object of my invention is to provide an improved machine tool having an improved hydraulic control and actuating system which makes the full power of the system continuously available for moving major components of the machine in relation to a workpiece even at a rapid traverse speed while at the same time eliminating the generation of heat to any appreciable degree in the fluid under all operating conditions.

A further object of my invention is to provide in a machine tool an improved hydraulic control and actuating system of the character set forth in the above object which is hydraulically alive and immediately responsive under all operating conditions to any demands made on the system.

A further object is to provide in self-contained machine tool unit an improved hydraulic control and actuating system, which under all operating conditions is immediately responsive to an electrical circuit control (operable from either a local or remote station) to immediately change the operating condition or cycle of the unit.

A further object is to provide an improved self-contained machining unit including an improved hydraulic actuation system which affords a more precise control over the feeding movement of the unit relative to a workpiece.

Another object of my invention is to provide improved control means for self-contained machine tool units which facilitates servicing of the control structure by relatively unskilled personnel in a manner which effectively avoids down time of the machining apparatus for servicing of the control structure.

Still another object is to provide improved machine tool control structure which can be serviced without danger of exposure to high voltages.

Still another object is to provide improved machine tool control structure which makes advantageous use of the capabilities of my improved self-contained machining units recited above.

Other objects and advantages of my invention will become apparent from the following description, taken with reference to the accompanying drawings, in which:

FIG. 1 is a partially sectioned side elevation of a self-contained machine tool unit constructed in accordance with my invention;

FIG. 2 is a rear end elevation of the unit taken with reference to line 2—2 of FIG. 1;

FIG. 3 is a fragmentary longitudinal sectional view of the unit taken along the line 3—3 of FIG. 2;

FIG. 4 is a transverse sectional view taken along the line 4—4 of FIG. 1;

FIG. 5 is a fragmentary sectional view taken generally along the line 5—5 of FIG. 4 and showing components of the rapid traverse pump and the pilot pump;

FIG. 6 is a fragmentary sectional view taken generally along the line 6—6 of FIG. 5;

FIG. 7 is a sectional view taken along the broken line 7—7 of FIG. 6;

FIG. 8 is a fragmentary end view of the auxiliary and traversing pumps taken with reference to the line 8—8 in FIG. 6;

FIG. 9 is a fragmentary sectional view taken generally

along the line 9—9 of FIG. 4 and showing feed pump control structure;

FIG. 10 is a detail view on an enlarged scale showing coacting spiral gears used in the driving transmission;

FIG. 11 is a bottom view of the self-contained slide assembly taken with reference to line 11—11 in FIG. 1;

FIG. 12 is a fragmentary lower end view of the translatory head taken with reference to the line 12—12 of FIG. 1;

FIG. 13 is a diagrammatic illustration of hydraulic actuating and control circuits used to controllably translate the slide assembly 12 along its support base;

FIG. 14 is a vertical sectional view of the master control valve assembly for the unit taken along the line 14—14 of FIG. 2;

FIG. 15 is a sectional view of the valve assembly taken along the line 15—15 of FIG. 14;

FIG. 16 is a fragmentary sectional view taken along the line 16—16 of FIG. 15;

FIG. 17 is a partially sectioned front view of the valve assembly;

FIG. 18 is a partially sectioned and somewhat simplified perspective view of the valve assembly;

FIG. 19 is a simplified vertical sectional view of the valve assembly showing the positional relationship of major parts positioned for energizing the actuator to effect feeding movement of a slide assembly;

FIG. 19A is a diagrammatic illustration of the hydraulic circuit corresponding to the valve positions in FIG. 19;

FIG. 20 is a fragmentary sectional view illustrating one hydraulic pilot control for the main valve;

FIG. 20A is a diagrammatic illustration of the hydraulic circuit of FIG. 20;

FIG. 21 is a fragmentary sectional view illustrating another hydraulic pilot control for the main valve;

FIG. 21A is a diagrammatic illustration of the hydraulic circuit of FIG. 21;

FIG. 22 is a simplified sectional view of the valve assembly corresponding to FIG. 19 but illustrating the position of the valves for traversing the slide assembly rearwardly;

FIG. 22A is a diagrammatic illustration of the hydraulic circuit of FIG. 22;

FIG. 23 is a fragmentary sectional view showing the main valve in neutral position;

FIG. 23A is a diagrammatic illustration of the hydraulic circuit of FIG. 23;

FIG. 24 is a view similar to FIG. 22 but illustrating the position of valve parts for rapidly traversing the slide assembly forward;

FIG. 24A is a diagrammatic illustration of the hydraulic circuit of FIG. 24;

FIG. 25 is a view similar to FIG. 24 but illustrating the valve element in neutral position;

FIG. 26 is a partially sectioned view taken from the line 26—26 in FIG. 2 and showing internal components of a manifold;

FIG. 27 is a fragmentary sectional view taken along the line 27—27 of FIG. 26;

FIG. 28 is a fragmentary view taken along the line 28—28 of FIG. 26;

FIG. 29 is a lay-out of a portion of the hydraulic system coacting with the master valve assembly and illustrating specific components of this system in cross section;

FIG. 30 is a simplified cross sectional view illustrating the relationship of hydraulic passages associated with one end of the main control element when the latter is in rapid traverse forward position;

FIG. 31 is a view similar to FIG. 30 but showing the main valve control element shifted to feed position;

FIG. 32 is a view similar to FIG. 30 but showing the valve element in rapid traverse return position;

FIG. 33 is a view similar to FIG. 30 but showing the valve element in neutral position;

FIG. 34 is a fragmentary sectional view taken along the line 34—34 in FIG. 31;

FIG. 35 is a partially sectioned perspective view of the end of the valve element illustrated in FIGS. 32—34;

FIG. 36 is a diagrammatic illustration of control circuits used to control the individual machining units in conjunction with an automatic machining installation;

FIG. 37 is a continuation of the circuit diagram of FIG. 36;

FIG. 38 is a diagram of power circuits for a plurality of machining units and associated automatic machining structure;

FIG. 39 is a diagram of solenoid circuits used in controlling machining apparatus;

FIG. 40 is a continuation of the diagram of FIG. 39;

FIG. 41 is a continuation of the diagram of FIG. 40;

FIG. 42 is a fragmentary side view showing a modified form of gears used to connect the power shaft with the drive shaft;

FIG. 43 is a fragmentary circumferential view showing the periphery of one of the gears of FIG. 42;

FIG. 44 is a fragmentary sectional view taken generally along the line 44—44 of FIG. 42;

FIG. 45 is a fragmentary sectional view taken along the slightly curving line 45—45 of FIG. 43 following the root of one of the gear teeth;

FIG. 46 is a fragmentary sectional view taken along the diagonal line 46—46 of FIG. 43; and

FIG. 47 is a fragmentary sectional view taken along the line 47—47 of FIG. 43.

General Description of Self-Contained Machine Tool Unit

Having reference to the drawings in greater detail, the self-contained machine tool unit 10, FIG. 1, constructed in accordance with my invention comprises a self-energized, self-controlled, and self-propelled machining head or slide assembly 12 supported for translation on a pair of longitudinal ways 16 on an elongated base 14. The base 14 is designed for installation on a larger bed (not shown).

The forward end 18 of the translatable slide assembly 12 is designed to carry a multiple spindle head or other machining attachment 20 (indicated in phantom in FIG. 1) which is powered by the slide assembly and translated toward and away from a workpiece (not shown) by controlled self-propelled movement of the slide assembly along the ways 16.

The slide assembly 12 comprises a main frame or housing 22 slideably supported on the ways 16 and surmounted on its rear end by an electric driving motor 24. The motor is connected by guarded V-belts 26 with a pulley 28, FIG. 3, on the rearwardly protruding end of a longitudinal power shaft 30 extending centrally through the housing 22. Support for the motor 24 is provided by a mount 32 which can be tipped about a hinge axis 34, FIG. 2, by a threaded adjusting element 37, FIG. 1, to vary the tension in the belts 26.

The housing 22 is formed by a hollow casting, denoted by the same reference numeral, which is internally shaped and adapted as will presently appear to define a reservoir 36 for lubricating oil and a reservoir 38 for hydraulic fluid, FIG. 3, which are completely isolated from each other so as to prevent the interchange of liquid from one to the other.

The lubricating oil reservoir 36 comprises space within a relatively large transmission chamber 39 in the forward end of the housing 22 and a hollow longitudinal shaft housing 40 extending rearwardly from the transmission chamber to the rear end of the housing 22 as shown in FIG. 3.

The rear end of the power shaft 30 is supported in the rear end of the shaft housing 40 by an anti-friction bearing 42. Annular seals 44 adjacent bearing 42 prevent the escape of lubricating oil around the shaft 30.

The power shaft 30 extends through the shaft housing

40 and across the transmission chamber 39 to a forward end projecting from the housing 22 and supported in the housing by an anti-friction bearing 46 and sealed by a seal 48.

A pinion 50 affixed to the forwardly projecting end of the power shaft 30 is employed in a conventional manner to transmit power to the drilling head or other attachment 20 mounted on the unit as recited.

A transverse drive shaft 52 journaled in the housing 22 at opposite sides of the transmission chamber 39 by anti-friction bearings 54, 56, as shown in FIG. 4, extends transversely across the power shaft 30 in overlying spaced relation to the latter.

A pair of spiral gears 58, 60 non-rotatably mounted on the respective shafts 30, 52, as shown in FIGS. 4 and 10, mesh with each other to transmit rotary motion to the drive shaft 52.

The left end of the drive shaft 52, FIG. 4, projects from the transmission chamber 39 through encircling oil seals 62 to drive a variable capacity feed pump 64 (to be described presently in greater detail) secured to the adjacent side of the housing 22 as shown.

The opposite end of the drive shaft 52 has a splined connection with a coaxial shaft 66 which powers a fixed displacement traversing pump 68 and a low volume pilot pump 70 mounted in tandem, as shown in FIGS. 4 and 6, on the adjacent side of the housing 22.

As will presently appear, fluid supplied under pressure from the traversing pump 68 and the feed pump 64 is utilized by improved control means provided by my invention to propel or translate the self-energized slide assembly 12 along the support ways 16.

Controlled translation of the slide assembly 12 is effected by means of a translating fluid motor 72, FIG. 1, comprising a longitudinal cylinder 74 affixed to the underside of the housing 22 between the ways 16 and containing a reciprocable actuating piston 76 connected to the rear end of the base 14 by a piston rod 78 extending through a seal 80 in the rear end of the cylinder 74. Thus, fluid supplied under pressure to either end of the piston 76 serves to translate the slide assembly 12.

Having reference to FIG. 3, it will be observed that the hydraulic fluid reservoir 38 completely surrounds the power shaft housing 40 and is filled with hydraulic fluid to a normal level, indicated by the numeral 82, located well above the housing 40 and above the major portion of the transmission chamber 39. The reservoir 38 is filled through a capped fixture 84 on one side of the housing 22, FIGS. 1 and 2, and the level of the fluid is observed through two vertically spaced windows 86, 88 in the housing 22 as shown in FIG. 1.

Hydraulic fluid is drawn into the traversing pump 68 through a suction line 90 connected to a highly efficient filter 92 in the lower portion of the reservoir 38, FIG. 3. Hydraulic fluid is returned to the reservoir 38 through a return line 94 discharging into the reservoir above the fluid level 82 as shown. This relationship of the return line to the intake filter 92 tends to create a circulation of fluid and hence an even temperature throughout the reservoir 38 and the adjacent machine structure.

As indicated in FIG. 4 lubricating oil is supplied to the bearings 54, 56 through conduits 96 from a lubricant pump to be described presently. A pool of lubricating oil 98 in the bottom of the transmission chamber 39 extends above the lower extremity of the gear 58 to a level which is limited by an overflow opening 99 formed in one side of the transmission chamber 39 as shown in FIG. 4.

As shown in FIGS. 11 and 12 the underside of the housing or slide frame 22 defines a pair of ways 100 conforming to the support ways 16 and slideably supporting the assembly 12 on the latter for translation of the base 14.

Each of the ways 100 is well lubricated by lubricant supplied to a zig-zag lubricating groove 102 in the way.

As is shown, lubricant is conducted into each groove 102 through three lubricant supplying fittings 104 longitudinally spaced along the ways 100 and forming components of a lubricant distribution system including distribution conduits 106 leading from a lubricant pump to be described presently.

FIG. 11 also illustrates in phantom the arrangement of conduits and piping, indicated generally by the numeral 108, extending across the housing 22 to interconnect improved hydraulic actuating and control structure provided by my invention to effect translation of the slide assembly 12.

It is desirable in some situations that the translatable head assembly 12 dwell in a forward position before returning to its starting position. As will presently appear, such dwell is produced with the aid of a positive stop which limits forward movement of the slide assembly 12 in a predetermined adjusted position. As shown, an adjustable positive stop for this purpose is provided by an adjustable stop screw 110, FIGS. 1 and 2, threaded into the forward end of the base 14 and extending rearwardly to engage the forward, hardened end of the actuating cylinder 74.

The base 14 also supports on one side, FIG. 1, a longitudinal mount 112 for a plurality of cam and switch control dogs, to be described presently, which are used to trigger control structure on the slide assembly 12 in accordance with its position on the base.

Traverse and Pilot Pumps

As shown in FIGS. 5 and 8, the previously mentioned traverse pump 68 used to power rapid traversing of the slide assembly 12 comprises a casing 114 bolted to the side of the housing 22 and containing internal bearings 116 journaling the previously mentioned pump shaft 66. The general construction of the pump 68 is of the type shown in my U.S. Patent No. 2,588,430 to which reference may be made for specific details. In general, however, the pumping action of this pump is produced by a central rotor 118 on the shaft 66 which carries a plurality of blades operating in an asymmetrical cavity as described in U.S. Patent No. 2,588,430.

Hydraulic fluid from the intake filter 92 is supplied through connected bores 120, 122 in the housing 22 and casing 114, as shown in FIG. 5, to the pump rotor 118 which discharges through an annular cavity 124 to an output line 126.

As shown in FIG. 2 the output line 126 extends downwardly to connect with an underlying manifold 128 secured to the frame 122.

A highly effective sealing unit 130, FIG. 6, encircling the inner edge of the pump shaft 66 prevents fluid from within the pump casing 114 from gaining entry into the lubricant containing transmission chamber 39. Connected bores 132 in the pump casing 114 and housing 22 carry hydraulic fluid back to the reservoir 38 from the outer end of the seal 130 thus avoiding fluid pressure on this seal.

The limited output, pilot pump 70 is a small gear pump 60 mounted on the outer end of the traverse pump casing 114 as shown in FIGS. 5 and 6 and driven by a shaft 134 connecting with the outer end of the shaft 66. Hydraulic fluid is supplied to the inlet of the pump 70 through a bore 136 in the pump casing 114. A discharge line 138 from the pump 70 extends down to the manifold 128 as shown in FIG. 2.

It is noteworthy that the intake bore 136 for the pilot pump 70 connects with the bore 122 at the intake 140 of the traverse pump 68, FIGS. 5 and 6, thus making operation of the auxiliary pump independent of the hydraulic operation of the traverse pump.

Feed Pump

The feed pump 64, FIG. 4, is a variable capacity positive displacement piston pump having a general construc-

tion similar to that illustrated in FIGS. 27-31 of my U.S. Patent No. 2,266,829 issued December 23, 1941, to which reference may be made for a disclosure of details not specifically described here.

In general, the pump 64 comprises a hydraulic fluid intake including intake check valves 142, FIG. 4, which supply fluid under pressure from either the traverse pump 68 or the pilot pump 70 to an annular array of radial pumping cylinders 144, only one of which is shown. Fluid is discharged under pressure from the cylinders 144 through outlet check valves 146 which connect with valve control structure to be described in detail presently.

A plurality of pistons 148 operating in the pump cylinders 144 are driven by an adjustable eccentric drive including an eccentric bearing race 150 mounted on an eccentric journal 152 projecting from the adjacent end of the drive shaft 52. The rotary position of the eccentric 150 on the journal 152 is adjusted by a manually adjustable sleeve assembly 154 to vary the effective stroke of the eccentric drive for the pistons 148. This adjustment determines the maximum stroke of the pistons 148 and hence the maximum pumping rate for any speed of the drive shaft 52.

Further provision is made for temporarily reducing the effective output rate of the pump 64 below its adjusted maximum rate. For this purpose an annular stop element 156 is used to limit the inward movement of the pistons 148 by the inlet pressure of fluid supplied to the cylinders 144. The construction and action of the adjusting element 156 is similar to that of the element 468 in my previously mentioned Patent No. 2,266,829.

A rotary adjustment of the element 156 serves to vary the instantaneous pumping rate of the pump 64.

Rotation of the element 156 is effected by a sector gear 158 connected through a shaft 160 with a second sector gear 162, FIGS. 4 and 9, meshing with a rack 166 extending into a sleeve 168 from a pump control 170 slidably mounted in a cylinder 172.

The piston 170 is urged by a spring 174 in a direction for increasing the output of the pump 64. It is moved in the opposite direction to reduce the output of the pump 64 by fluid admitted into the cylinder 172 through a pilot valve 171, FIG. 9, controlled by a solenoid 173 in a manner to be presently described.

The extent to which the output of the pump 64 is reduced by the admission of fluid into the control cylinder 172 is determined by an adjustable stop 176 threaded into the sleeve 168 and engaging the adjacent end of the rack 166.

A pointer 178 fixed to the projecting end of the pump control shaft 160 as shown in FIG. 4 cooperates with the scale 180, FIG. 1, to provide a visual indication of the instantaneous feed pumping rate. All this pump adjusting structure is mounted in a casing element 182 affixed to the housing 22 as shown in FIGS. 1 and 4.

Hydraulic Slide Actuating and Control System

The hydraulic system used to power and to control translation of the head assembly 12 is illustrated diagrammatically in FIG. 13.

As illustrated in the lower right-hand portion of FIG. 13, the variable capacity feed pump 64 (designated by a legend including the symbol "PV" denoting a pump with a variable capacity), the traversing pump 68 (denoted by a legend including the abbreviation "PF" denoting a pump with a fixed capacity), and the pilot pump 70 (designated by suitable legend including the abbreviation "PF" for fixed capacity pump) are all driven by the electric motor 24, as previously described.

The means used to control the direction of fluid from these pumps to the hydraulic actuator 72 for the head assembly comprises a master valve element 182 illustrated diagrammatically in the upper central portion of FIG. 13 and having four effective positions corresponding to four effective conditions of energization of the hydraulic actuator 72. The positions, as indicated by legends in FIG. 13, are rapid reverse, neutral, feed forward, and rapid advance or traverse forward.

As will presently appear, the master control valve element 182 controls hydraulic energization of the actuator 72 directly and through the agency of a slave valve element 184 appearing in FIG. 13 below the master element and having two effective positions as indicated.

The master valve element 182 is controlled as indicated by a mechanical actuator 186 and by two opposed hydraulic actuators 188, 190 which are in turn controlled respectively by a three position pilot valve 192 and a two position pilot valve 194.

As will presently appear, a remote control solenoid 196 adapted for energization from a remote station is used to shift the pilot valve 194 from the normal position shown, FIG. 13, to a rapid advance position which energizes the actuator 190 to shift the master valve element 182 into a position which effects a rapid traversing of the head assembly 12 in a forward direction.

The other pilot valve 192 is shifted from a normal position indicated in FIG. 13 to a second or "dwell" position by a cam follower 198, FIGS. 13 and 17, which is actuated by a cam 200 in accordance with the position of the slide assembly 12 on the base 14 and substantially concurrently with positive stopping of the head assembly by the stop element 110, FIG. 1, to provide a desired dwelling of the machine in its extreme forward position, as will be presently described.

A solenoid 204 connected with the pilot valve 192, FIG. 13, shifts the valve element 182 beyond its dwell position to a third position, which energizes the hydraulic actuator 188 to shift the master valve element 182 immediately to its rapid reverse position. The solenoid 204 can be controlled from a remote position to effect a quick reversal of forward movement of the head assembly 12 in the event of tool breakage or any other emergency.

The master valve element 182 and the slave valve 184 are mounted in a common housing 206 which supports at its opposite ends the respective pilot valves 192 and 194 together with the solenoid and mechanical actuators 196, 198, and 204. This valve housing 206 is attached to one side of the housing or frame 22 below the feed pump 64 as shown in FIG. 1, and in overlying relation to the control dog support 112 on the base 14. It will be noted with reference to FIGS. 14 and 17 that the positions of the pilot valves 192 and 194 relative to the master and slave valve elements 182, 184 are reversed from the relative positions of these elements as they appear in FIG. 13. This results from the transposal of the relative positions of elements in the diagrammatic layout in FIG. 13 for simplicity in illustration.

Hydraulic conduits or passages which contain hydraulic fluid under an elevated pressure are illustrated by solid lines in FIG. 13. Other conduits or passages which are not under pressure and which usually connect with the fluid reservoir 38 are illustrated by dotted lines.

Thus, the output side of the traversing pump 68 is connected through a line 207 with a normally open flow modulator valve 208 which discharges back into the hydraulic reservoir 38. The flow modulator valve 208 is a free flowing valve which, when open, eliminates all back pressure on the continuously driven traversing pump 68. Consequently, as will presently appear, the traversing pump 68 circulates fluid through the modulator valve 208 with only a nominal absorption of energy from the drive to the pump and, hence, effectively avoids heating of the fluid circulated through this pump.

The modulator valve 208 is closed only when the master valve 182 is positioned for rapid traverse of the slide assembly 12 either forward or rearwardly. Such closing of the modulator valve is effected by control fluid supplied to the modulator valve, as will presently appear, through a pilot pressure line 209 communicating with the master valve 182.

A check valve 212 connected to the line 207 ahead of the modulator valve 208 connects the outlet end of the traversing pump 68 to a pressure line 214 leading to the master and slave valve element 182 and 184.

The discharge side of the pilot pump 70 connects with the line 214 downstream of the check valve 212 to maintain pressure in the line 214 when the modulator valve 208 is open.

A traverse relief valve 216 connected to the line 214 limits the pressure in this line to a value well within safe limits in the event of abnormal conditions blocking rapid traverse movement of the slide assembly 12 on the ways 16.

Hydraulic pressure is supplied to the intake of the feed pump 64 through a charge line 218 from the slave valve 184, which extends through a strainer or filter 220 designed to eliminate all foreign particles from fluid entering the feed pump.

The outlet of the feed pump is connected through a line 222 with the end of the actuating cylinder 72 to which fluid is supplied under pressure to advance the slide assembly 12 forwardly. It is noteworthy with reference to FIG. 13 that this is the end of the cylinder 72 which faces the full area of the piston 76 undiminished by the transverse sectional area of the piston rod 78.

A safety feed relief valve 224 connected with the line 222 limits the pressure transmitted through the line 222 to the actuator 72 to a safe value during a feeding cycle. Since resistance to forward movement of the slide assembly 12 during a feeding cycle is normally greater than that during a traversing cycle, the safety valve 224 is set to open at a higher pressure than the traverse relief valve 216.

The cylinder pressure line 222 also communicates with the slave valve 184, FIG. 13. Another cylinder pressure line 226 connects both the master valve 182 and the slave valve 184, as shown, with the piston rod end of the actuator cylinder 74.

A return line 228 to the reservoir 38 communicates with both the master and slave valve 182, 184, and with both of the pilot valves 192, 194.

Turning now to the actual structure of the control system, it will be observed with reference to FIG. 29 that the several conduits 228, 222, 214, 226 and 209 extend transversely through the slide housing 22 to connect with the ported back side of the previously maintained valve housing 206 and communicate with both the master and slave valve elements 182, 184.

As shown in FIGS. 14 and 16, the master valve 182 and the slave valve 184 are spool valves slidably mounted respectively in parallel valve cylinders 230, 232.

The master valve element 182 has four operating position longitudinally spaced from each other. As shown in FIGS. 14 and 24, the master valve 182 is in its rapid traverse forward position in the extreme right end of its cylinder 230, FIG. 22. The rapid traverse return position of the valve element 182 is at the extreme left end of the cylinder 230, FIG. 22. In its neutral position, FIGS. 16 and 25, the master valve element is displaced somewhat to the right of its rapid traverse return position, FIG. 22. The forward feed position of the master valve element 182, FIG. 19, is located somewhat to the right of the neutral position, FIG. 16.

The master valve element 182 is shifted from one operating position to another hydraulically by the previously mentioned pilot valves 192, 194 mounted on opposite ends of the valve housing 206 as shown in FIG. 14 and also by means of a mechanical actuating shaft 234 rotatably mounted in a vertical position in the housing 206 as shown in FIG. 15. The shaft 234 is connected with the valve element 182 by means of a finger 236 on the upper end of the shaft, which extends into an actuating slot 238 in the upper side of the master valve element. The lower end of the master valve actuating shaft 234 depends below the housing 206 and connects with a pair

of actuating cams 240, 242, which co-act with actuating dogs 244 adjustably positioned on the longitudinal support 112 on the base 14 as shown in FIG. 1.

The dogs 244, only one of which is shown in FIG. 1, are so positioned that on rearward movement of the slide assembly 12 to its return or starting position, one of the dogs 244 engages the lower control cam 242 and rotates the shaft 234 sufficiently to shift the master valve element 182 from its rapid traverse return position, FIG. 16, to its neutral position, FIG. 16.

While the master valve element 182 is normally shifted from its neutral position to its rapid traverse forward position, FIG. 14, by the pilot valve 194, it can be shifted to rapid traverse forward position by means of a tool (not shown) inserted in an opening 246, FIG. 15, and a pointer element 248 affixed to the lower end of the shaft 234.

When the slide assembly 12 has advanced forwardly into proximity to a workpiece, the upper control cam 240 engages another of the dog elements 244 to shift the valve element 182 from its traverse forward position 214 to the feeding position shown in FIG. 19. The slide assembly 12 continues forward at a feeding speed to its extreme forward position where the cam 240 engages another dog 244 which shifts the valve element 182 back to its traverse return position shown in FIG. 21.

The slave valve 184 has two operating positions, a feeding position in the extreme right end of the cylinder 232, FIG. 19, to which it is urged by a spring 250 in the left end of the element 184 when the master valve 182 is in its feeding position, and a second position in the left end of the cylinder 232 to which the element 184 is moved by hydraulic fluid under pressure admitted into the right end of the cylinder 232 when the valve element 182 is in its other three positions.

The hydraulic connections made by the valves 182, 184 in their various positions are more easily visualized with reference to the simplified illustrations of structure appearing in FIGS. 17 to 25.

Thus, as shown in FIG. 24, the fluid supply line 214 from the traversing pump 68 is connected to the line 222 leading to the slide assembly advancing end of the hydraulic actuator 72. This connection is made from the supply line 214 through a master cylinder enlargement 254, around a master valve element neck 256, through a master cylinder enlargement 258, through a valve body bore 260, through a slave cylinder enlargement 262, around a slave valve element neck 264, and through a slave cylinder enlargement 266 to the line 222.

At this time fluid is displaced from the opposite end of the actuator 72 through the line 226, which is connected to the reservoir 38 through a port 268 in the valve housing 206, a central bore 270 in the master valve element 232, an orifice 272 in the right hand end of the bore 270, FIG. 24, and a master cylinder enlargement 274, which communicates with the reservoir 38.

A plunger 276 mounted in the right hand end of the master cylinder 182, as shown in FIGS. 14 and 24, is urged by a spring 278 in an axial direction to constrict the orifice 272 yieldably to create a moderate back pressure on the fluid supply to the orifice 272. The use of this back pressure on the orifice 272 in valve control operations will be more specifically described presently.

While the master valve element 182 is in its rapid traverse forward position, FIG. 24, the slave valve element 184 is retained in its position at the left end of the cylinder 232 as shown by fluid from the pump 68 admitted under pressure into the right end of the cylinder 232 through bores 280 in the housing 206, through a master cylinder enlargement 282 and a short axial bore 284 and the valve element 182 extending between the enlargement 282 and the enlargement 254 communicating with the pump 68.

It will be noted again with reference to FIG. 24 that the feed pump 64 operates during a traverse forward

cycle merely to circulate fluid between the slave valve enlargement 266 and the line 222 communicating with the enlargement 266. As illustrated in FIG. 25, which also shows the slave valve element 184 in its extreme left position, the inlet of the feed pump 64 is connected to the cylinder enlargement 266 through a valve housing port 236 and a short axial bore 283 in the slave valve element 184.

During rapid traverse of the slide assembly 12, the modulator valve 208 which normally unloads the traverse pump 68, is closed by pilot pressure controlled by porting in the master valve element 182 to be described presently.

FIG. 24A diagrammatically illustrates the hydraulic connections made through the master and slave valve assemblies during a rapid traverse forward cycle. Legends and symbols used in this figure, as well as in FIGS. 19A, 20A, 21A, 22A, and 23A conform to JIC (Joint Industry Conference) standards.

When the slide assembly 12 has traversed forwardly to the desired extent, the master valve element 182 is shifted to its feeding position, FIG. 19. The right hand end of the slave cylinder 232 is connected to exhaust through the bore 280, master cylinder enlargement 282, and a short axial bore 286 extending through the left end of the valve element 182 to the left end of the cylinder 230, which is connected to exhaust through the pilot valve 194 as will be presently explained.

The slave valve 184 is shifted to the right by the spring 250 to connect the intake of the feed pump 64 with the line 226 from the slide returning end of the actuator 72. The return line 226 communicates with a valve housing bore 290, FIG. 16, which, as illustrated in FIG. 19, directs fluid around a slave valve neck 292 to the ported connection 286 with the intake of the feed pump 64 as shown. Communication between the slave valve enlargement 266 and the bore 260, FIG. 22, is blocked off by the valve element 184, FIG. 19.

Since advancement of the slide assembly 12 extends the piston rod 78 from the actuator cylinder 74, additional fluid must be supplied to the feed pump to compensate for the volume of the piston rod moving out of the actuator cylinder. This additional fluid is supplied to the feed pump 64 through a pump housing bore 293, FIGS. 16 and 19, extending between the master cylinder enlargement 254 and the bore 290 leading to the feed pump inlet. It will be understood that even though the traverse pump 68 is unloaded at this time by the modulator valve 208, the low output pilot pump 70 continues to supply fluid under pressure through the line 214 to the master cylinder enlargement 254 where a back pressure is maintained by the restrictive effect of the orifice 272.

It should be appreciated that during feeding movement of the slide assembly 12, all of the energy imparted to the feed pump 64 is transmitted through the hydraulic fluid to advance the slide assembly with no appreciable heating of the hydraulic fluid. The traversing pump 68 is unloaded so that it does not heat the hydraulic fluid. The volumetric output of the pilot pump 70 in excess of the make-up fluid supplied to the feed pump is so low and the back pressure of the orifice 272 is so low that the hydraulic fluid is not appreciably heated by the pilot pump.

A simplified diagrammatic illustration of the hydraulic circuits operating during feeding movement of the slide assembly 12 is shown in FIG. 19A.

When the slide assembly 12 reaches its extreme forward position, the master valve 182 is shifted to its rapid traverse return position, FIG. 22, as previously explained. This connects the traverse pump 68 through the master cylinder enlargement 254 and around the master cylinder neck 256 with the port 268 communicating with the line 226 leading to the return end of the actuator 72. At the same time, the master cylinder enlargement 282 supplied with fluid under pressure from around the master valve neck 256 communicates through the bore 230 with

the right end of the slave cylinder 232 to hold the slave valve 184 in the left end of its cylinder as shown, FIG. 22. This connects the line 222 from the advancing end of the actuator 72 through the slave cylinder enlargement 266, around slave valve neck 264, through slave cylinder enlargement 262, bore 260, and master cylinder enlargement 258, around master valve neck 294, and through master cylinder enlargement 274 to the reservoir 38.

The hydraulic circuit operating during rapid traverse return is illustrated diagrammatically in FIG. 22A.

Upon return of the slide assembly 12 to its starting position, the master valve element 182 is shifted to its neutral position, FIG. 25.

This neutral position of the master valve element 182 cuts off the actuator line 226 from the pressure line 214 from the pilot pump 70. However, the output of the pilot pump is connected around the master valve neck 256 to the master valve enlargement 282, which communicates with the bore 280 to hold the slave valve element 184 in the left end of its cylinder. The pilot pump 70 works against only the back pressure of the orifice 272 and effects no appreciable heating of the hydraulic fluid. The traverse pump 68 is unloaded. The feed pump 64 merely circulates fluid between its own inlet and outlet in the same manner as that previously described in connection with a rapid traverse forward cycle.

The hydraulic circuit established when the master valve element 182 is in neutral position is illustrated diagrammatically in FIG. 23A.

Pilot Control of Master Valve Element

As previously intimated, the pilot valve 192, FIGS. 14 and 18, is used in conjunction with the cam and follower actuators 200, 198 for this valve and with the mechanical slide assembly stop 110, FIG. 1, to provide for dwelling of the slide assembly in its extreme forward position.

As best shown in FIG. 18, the pilot valve 192 is formed as a spool valve having a relatively long neck 300 located above and spaced from a second neck 302 on the valve. The valve 192 co-acts with four ports comprising, as shown in FIG. 18, a port 304 connected through a bore 306 in the pilot housing 308 and the main valve housing 306 with the master valve cylinder enlargement 254, a port 310 connected through a bore 312 with a port 314 in the right end of the master valve cylinder 230, FIGS. 17 and 18, a port 316 connected through a bore 318 with the extreme right end of the master cylinder 230, and a port 324 connected to exhaust. An adjustable needle valve 320 interposed in the bore 318 as it extends through the pilot valve housing 308 provides for an adjustment of the rate of fluid flow through the bore 318 to control the dwell time as will presently appear.

It should be mentioned here that when the machine is set up to dwell in its forward position, the control dog 244 which normally shifts the master valve element 182 from its feed position to its rapid traverse return position, as previously explained, is adjusted to shift the master valve element only to its neutral position concurrently with stopping of forward movement of the slide assembly by the positive stop 110.

At the same time, the cam 200 shifts the pilot valve 192 to the position shown in FIG. 18 in which the neck 300 is aligned with the three ports 304, 310, 316. The pilot pump 70 communicating with the master cylinder enlargement 254 supplies fluid through the needle valve 320 to the right hand end of the master cylinder 230. This produces a slow progressive movement of the master valve 182 from its neutral position toward its rapid traverse return position. At this time the port 314 is blocked by the right end of the master valve 182 as shown in FIG. 18. The slide assembly 12 continues dwelling in its forward position until a sufficient volume of fluid has passed through the needle valve 320 to

displace the master valve 182 beyond its port 314, at which time fluid under pressure from the port 310 flows through the unrestricted bore 312 to snap the master valve 182 to its rapid traverse return position.

During dwelling of the slide assembly in its forward position, the residual pressure in opposite ends of the actuator cylinder 74 tends to urge the slide assembly against the positive stop 110, due to the differential pressure area of the piston 76 resulting from the presence of the piston rod 78 on only one end of the piston.

Energization of the solenoid 204, at any time, shifts the pilot valve 192 into the position shown in FIG. 21 in which it effects an immediate shifting of the master valve 182 into its rapid traverse return position. Thus, as shown, the pilot valve 192 is displaced upwardly beyond its "dwell" position to register the neck 302 with the fluid supply port 304 and a lower pilot valve port 322 which connects with the bore 318 downstream of the needle valve 320, FIG. 18, and, hence, directly with the right end of the master cylinder 230. Thus, upon energization of the solenoid 204 from a local or remote control station, the machine is rapidly put into a rapid traverse cycle. The hydraulic pilot circuit used in this operation is illustrated diagrammatically in FIG. 21A.

It is also noteworthy that a spring 324 urges the valve element 192 downwardly toward a normal position (not shown) in which the neck 302 connects the port 322 and, hence, the right end of the master cylinder 230, with an exhaust port 324, FIG. 18.

The pilot valve 194, FIG. 14, used to effect a shifting of the master valve 182 to its forward traverse position upon energization of the solenoid 196, is also a spool valve, which, in its normal position shown in FIG. 14, connects a bore 326 from the left end of the cylinder 230 with an exhaust bore 328 leading through the valve housing 206 to the master cylinder enlargement 274 communicating with the fluid reservoir 38. Energization of the solenoid 196 moves the pilot valve 194 to the position illustrated in FIG. 20 in which the pilot valve connects the cylinder bore 326 with a bore 330 communicating with the master cylinder enlargement 254 which is supplied with fluid under pressure. This directs fluid into the left end of the cylinder 230 to produce the desired immediate shifting of the master valve 182 to its rapid traverse forward position.

The pilot valve circuits operating upon energization of the solenoid 196 are illustrated diagrammatically in FIG. 20A.

Valve Porting for Controlling Traverse Pump Modulator Valve

The valve porting used to control the modulator valve 208 is illustrated on an enlarged scale in FIGS. 30 to 35, which also show the master valve porting used to control the slave valve 184.

The two ports 280 and 280a are separate branches of the master valve end of the bore 280 leading to the right end of the slave valve cylinder 232 as shown in FIG. 14. The two ports designated, respectively, as 280 and 280a both communicate with and are, in fact, branches of the master valve end of the previously mentioned charge line 209, FIG. 13, leading to the modulator valve 208.

The previously mentioned axial bore 284 in the left end of the master valve element 182 extends to the left from the master valve neck 256 where the bore 284 receives fluid under pressure from the master cylinder enlargement 254. Two axially spaced ports 284a, 284b extend radially outward from the bore 284 as shown in FIGS. 30 and 35.

The bore 286 extends axially into the valve element 182 from the left end of the element where the bore communicates with the reservoir 38 through the bore 326. Two axially spaced ports 286a, 286b extend radially outward from the bore 286 as shown in FIG. 35.

The relationship of the fluid pressure supply ports

75

284a, 284b to the modulator valve port 209 and the slave cylinder port 280 is such that the fluid pressure ports 284a, 284b are connected with the ports 209, 280 only when the master valve 182 is in its feed position shown in FIG. 30. Also, when the master valve element 182 is in its rapid traverse forward position, FIG. 30, the two exhaust ports 286a and 286b are out of alignment with the ports 209a and 280a. Consequently, the modulator valve 208 is closed and control fluid is supplied to the slave valve 184.

When the master valve 182 is in its feeding position shown in FIG. 31, both bores 209, 280 are cut off from the fluid supply bore 284 and the modulator valve line 209a and the bore 280a are connected to exhaust through the ports 286a, 286b.

When the master valve 182 is shifted to its rapid traverse return position, FIG. 32, all four of the ports 209, 209a, 280, 280a are supplied with fluid under pressure from the space around the valve neck 256.

Movement of the master valve 182 to its neutral position shown in FIG. 33, continues the supply of fluid under pressure to the slave valve port 280, as shown, but connects the modulator valve port 209a to exhaust through the port 286b.

Structure of Miscellaneous Components

The previously mentioned manifold 128 mounted on one side of the housing 22 below the traverse and pilot pumps 68, 70 houses, as shown in FIGS. 26-28, the previously mentioned check valve 212, FIGS. 13 and 26, on the outlet side of the traversing pump 68, the traversing pump modulator valve 208, the traverse pressure relief valve 216 and a lubricating pump 340.

The check valve 212 is biased against a resilient seat 342 by a spring 344. The bore 207 in the manifold 128 communicating with the upstream side of the check valve 212 is actually supplied with fluid from the pipe 126 extending downward from the traversing pump 68.

The modulator valve 208, FIG. 28, comprises a plunger 346 normally spaced from a circular valve seat 348 communicating with the bore 207. A return line 350 communicating with the downstream side of the valve seat 348 extends back to the reservoir 38. Fluid supplied under pressure from the pilot pump 70 through the charge line 209 enters a cylinder 352 behind the modulator valve plunger 346 to urge the plunger into closed position against the seat 348. Since the transverse sectional area 346 in the cylinder 352 exceeds the effective area of the seat 348, the differential fluid pressure on the plunger 346 retains it in closed position until the charge line 309 is connected to exhaust.

An interconnecting bore 214 extends through the manifold 128 from the downstream side of the check valve 212 into the lower end of a pressure cylinder 354, FIG. 26, in the traverse relief valve 216, where the pressure of fluid from the pump 68 acts on a plunger 356 to move the latter against a spring 358 to open the valve 216 to exhaust through the connected drain line 228, FIGS. 26 and 29, when the traversing fluid pressure exceeds a predetermined value.

The feed relief valve 224 is mounted in the housing 22, FIG. 29. As shown, feeding fluid under pressure is supplied from the line 222 into the bottom of a relief valve cylinder 360 where it acts against a plunger 362 to move the latter against a spring 364 to open the valve into the return line 228 when the pressure in the line 222 exceeds the predetermined level which is well within the safety limits of the hydraulic system.

The piston pump strainer 220 is suitably mounted to the housing 22 and connected in the charge line 218 to the feed pump as is shown in FIG. 29.

The lubricating pump 340 mounted in the manifold 128, FIG. 26, is operated by the changes in the pressure line 207 from the traversing pump 68 effected by opening and closing of the modulator valve 208. Thus, as

shown, the upper end of the lubricant pump 340 communicates with the passage 207 whereby, upon closure of the modulator valve 203, fluid under pressure in the line 207 moves a pump plunger 366 downwardly against a spring 368 to force lubricant from a pumping cylinder 370 out through a connected lubricant distributing line 106 which carries lubricant to the slide ways and grooves 100 as previously explained in connection with FIG. 11. Lubricant is admitted to the cylinder 370 through an inlet 372 as is shown in FIG. 29.

Changes in fluid pressure in the line 207 are also used to operate a leakage pump 374, FIG. 29, mounted in the housing 22. As shown, fluid admitted from the line 207 into the pump 374 moves a pumping plunger 371 downwardly against a spring 378 to force fluid from a cylinder 386 out past a float valve 382 to return to the reservoir 38 through the line 228. The pump 374 is placed in a low point in the structure where the pump intake 384 picks up any leaked hydraulic fluid.

Automatic Control of Machining Units in Successive Machining Stations

Self-contained machining units 10 provided by my invention are well adapted to perform successive machining operations at successive stations of automatic machining apparatus for "progress-thru" machines in which the individual machining units 10 are coordinated with automatic workpiece transfer apparatus, workpiece clamping devices, and the like to automatically carry through a series of machining operations on a procession of workpieces fed through the automatic machinery.

While any number of self-contained machining units 10 embodying my invention can be incorporated into an automatic production line of machining apparatus, the controls for only two such units are specifically illustrated in the diagrammatic control circuits shown in FIGS. 36 to 41.

FIG. 38 illustrates the power supply to the energizing motors 24, 24a of two machining units 10, the power supply to the driving motor 562 of an automatic fixture used to supply workpieces to the machining units, and the power supply for four control power supply lines A, B, C and D for controls to be presently described. Three phase power is supplied from lines 594 through a triple pole switch 506 to lines 503 leading to a step down transformer 510 for the control power lines A, B, C and D and to switches for the fixture motor and the machining unit motors to be referred to later.

For convenience in description individual segments of the overall control apparatus which appear on separate lines or levels in the diagrammatic illustrations in FIGS. 36, 37, 39, 40 and 41 are designated with reference numerals between the numbers 400 and 500 as shown. In the ensuing description specific elements of the control circuit will be located by reference to the number of the line in the diagram in which the element appears.

The first step in putting the machining apparatus into operation is to depress the master start switch 512 in line 1, FIG. 36, which energizes the master solenoid 514 through the master stop switch 516, the circuit being completed through the control power lines B and C which are energized through the transformer 510 as previously described in relation to FIG. 38.

For the most part, the solenoids used in the controls to be described are operators for relay switches. For clarity, the switches operated by a solenoid are designated by the same reference numeral with the addition of a hyphenated numeral suffix as will presently appear.

Energization of the master solenoid 514 closes two master switches 514-1 and 514-2, line 402, which respectively connect the control power lines B and C with control power lines F and G.

At this point it will be noted that in the diagrammatic illustration of the control circuits both the control power lines F and G extend from FIG. 36 over to FIG. 37

so that the latter is in effect a continuation of FIG. 36. Master pilot light 518 in line 403 is energized upon closing of the master switches in line 402 as described. A third switch 514-3 in line 402, closed by the master solenoid 514, continues energization of the latter after pressure is removed from the start switch 512.

The controls illustrated in FIGS. 36 and 37 control operation of an integrated section or group of machining apparatus which operates as a coordinated entity and includes a plurality of stations each of which comprises a machining unit 10.

The controls for station number 1 are illustrated diagrammatically in line 451 to 464 in FIG. 37. A similar set of controls for station number 2 is illustrated diagrammatically in lines 467 to 480. Lines 441 to 446 illustrate connections for controlling additional stations if they are in fact used as a part of the section of the machinery for which controls are illustrated. These will be referred to presently in greater detail.

Coming back to the operating procedure, the machinery section start switch 520, line 404, is depressed to energize the section solenoid 522 through section stop switch 524 and fixture motor overload switches 526, line 404 in FIG. 38. Energization of the section solenoid 522 is continued around switch 520 by section solenoid switch 522-1.

Section solenoid switch 522-2, line 405, closes to connect control power line F through a conductor 526 to energize station solenoid 528 in line 440. This solenoid closes a switch 528-2 to connect control power line F with a conductor 530, line 441, leading as shown in FIG. 37 to controls for additional stations if any.

Energization of station solenoid 528 closes switch 528-1 in line 451 to energize unit number one motor control solenoid 529 in line 452 through one pole of a double pole selector switch 531 set to automatic position as shown.

The motor control solenoid 529 closes three power switches 529-1 to connect the power lines 598, FIG. 38 to energize the unit number 1 motor 24.

Similarly, station solenoid switch 528-2 is closed in line 467 to energize motor control solenoid 533, line 468, through one pole of a double pole selector switch 535 set to automatic position as shown. Motor switches 533-1 operated by the motor control solenoid 533 connect the motor 24a of the number 2 unit to energizing power lines 503 as shown in FIG. 38.

Energization of section solenoid 522, line 404, also closes a switch 522-3, line 405 to energize fixture motor solenoid 532 which closes fixture motor switches 532-1, FIG. 38, to energize the fixture motor 502.

As shown in line 406, the fixture motor solenoid 532 can be energized independently of the section solenoid switches by closing a fixture motor start switch 534 to energize the fixture motor solenoid through fixture motor stop switch 536. Such energization of the fixture motor solenoid 532 is continued around the switch 534 by solenoid switch 532-2.

The fixture motor 502, FIG. 38 drives a pump (not shown) in the machining section to supply hydraulic power for transferring workpieces from one position to another and for clamping workpieces in workholders.

A pilot lamp 538 in line 409 is energized to indicate to the operator that all of the stations in the section are in a state of readiness for a machine cycle to begin. This section ready light 538 is controlled by circuits associated with the respective stations as will be presently explained in further detail. Briefly however, a station or unit ready solenoid for station number one is energized in line 459 when station number one is in a state of readiness. This closes a ready switch 540-1 for unit or station number 1 in line 447. Similarly, a ready solenoid 542 in line 475 is energized when station number two is ready. This closes a second ready solenoid switch 541-1 in line 447 to energize the station ready solenoid 544. It

will be understood, that additional ready switches are provided in line 447 for any additional stations used.

Station ready solenoid 544 closes a switch 544-1 in line 448 to energize section ready solenoid 546 in line 408. Solenoid 546 in turn closes switch 546-1 to energize the section ready pilot light 538 in line 409 previously mentioned.

As will presently appear, the machining apparatus of the section can be set for automatic operation to automatically transfer, clamp, and machine workpieces as long as workpieces are supplied to a loading station for the station.

A selector switch 548 in lines 411, 412, and 414 can be set to either one of three positions, manual, semi-automatic, or automatic. The ensuing description will describe automatic operation of the machine in which the selector switch 548 is set in its automatic position illustrated in FIG. 36.

With the selector switch 548 set to automatic and the section ready light 538 on, the operator depresses the cycle start switch 550 in line 410 to energize the automatic solenoid 552 through a previously closed section ready switch 546-2. Energization of the automatic relay 552 is maintained through the switch 546-2, line 410, normally closed emergency return switch 554 and automatic relay switch 552-1 in line 411 and through selector switch 548 and normally closed unclamped switch 556 in line 412.

Energization of automatic relay 552 closes automatic relay switch 552-2, line 416, to energize transfer forward relay 558, line 415, through previously closed ready switch 546-3, normally closed clamp switch 560-1 and unclamp switch 562-1, which is previously closed by energization of unclamped solenoid 562 in line 429.

Energization of transfer forward coil 558, line 415, closes transfer forward switches 558-1 and 558-2 in line 436, FIG. 39, to energize transfer forward valve operating coil 564 to direct hydraulic fluid pressurized by the motor 502 into hydraulic structure which shifts a transfer bar into its forward position.

When the transfer bar reaches its forward position, a double pole limit switch 566, lines 417 and 418 is energized to turn on signal light 568 in line 417 indicating that the transfer bar is in its forward position.

Transfer bar limit switch 566 also energizes the clamp solenoid 560, line 419, through closed automatic relay switch 552-3, and normally closed unclamp switch 562-2. Energization of the clamp solenoid 560 is continued upon opening of the limit switch 566 by clamp solenoid switch 560-2.

Energization of the control clamp solenoid 560 closes clamp switches 560-3 in line 438 to energize clamping of valve solenoid 570 which operates a hydraulic valve to admit fluid into structure which clamps a workpiece in a workholder (not shown) for machining by the successive machining units 10.

Proper location of a workpiece in its workholder closes located switch 572 in line 421. The application of proper clamping pressure to the located workpiece closes a clamp pressure switch 574 in line 421 to energize through the located switch 572 clamped solenoid 576. This closes clamped switch 576-1 in line 422 to energize clamped signal light 578.

A clamped switch 576-2 in line 425 energizes a head advancing solenoid 580 through automatic solenoid switch 552-4 solenoid on cycle switch 582-1 and ready solenoid switch 546-4. The cycle on solenoid switch 582-1 is previously closed by cycle on solenoid 582 in line 414, which is energized simultaneously with the transfer of forward solenoid 558. Energization of the cycle on solenoid 582, however, is continued independently of the unclamp solenoid switch 582-1, line 415, through cycle on solenoid switch 582-2 and ready solenoid switch 546-5 in line 414.

Transfer return solenoid 584 in line 423 is energized

through automatic solenoid switch 552-5, clamped solenoid switch 576-3, and normally closed transfer return switch 586-1. As will presently appear, normally closed switch 586-1 is subsequently opened by transfer return solenoid 586 in line 428.

Energization of advance heads relay 580, line 425, closes advance head solenoid switch 580-1 in line 427 to energize a conductor 588 leading to line 442, FIG. 37, to energize the advance solenoid 590 through station ready solenoid switch 546-6 and normally closed station emergency solenoid switch 592-1. As will presently appear, the station emergency solenoid switch 592-1 can be opened by energization of the station emergency solenoid 592 in line 444.

Energization of the advance solenoid 590, line 442 closes station advance solenoid switch 590-1 in line 454 to energize the unit number 1 advance solenoid 594, line 455, through one pole of selector switch 531 (which is set to automatic position as shown) and a unit number one ready solenoid switch 540-2 previously closed by unit number one ready solenoid 540 in line 459. Similarly, closure of a station advance solenoid switch 590-2 in line 470 energizes unit number two advance solenoid 598 in line 471 through one pole of selector switch 535 set to automatic position as shown and unit number two ready solenoid switch 542-2 previously closed by energization of unit number two ready solenoid 542 in line 475.

The unit number one advance solenoid 594, line 455, closes unit advance solenoid switches 594-1 and 594-2 in line 481 to energize the pilot valve solenoid 196, FIGS. 13, 14 and 40 to effect rapid traverse advancement of the self-contained machining unit number one. It will be recalled that the solenoid 196 controls the rapid traverse forward pilot valve 194 for the machining unit 10. Similarly, the unit number two advance solenoid 598, line 471, closes switches 598-1 and 598-2 in line 483, FIG. 41, to energize the rapid traverse forward solenoid 196a for machining unit number 2.

Advancement of the machining units in stations number one and two opens unit number one return switch 602 in line 459 to de-energize unit number one ready solenoid 540 and opens unit number two return switch 604 in line 475 to de-energize unit number two ready solenoid 542. The result is to open switches 540-1 and 542-1 in line 447 to de-energize station ready coil 544 opening switch 544-1 in line 448 to de-energize section ready solenoid 546 in line 408.

De-energization of section ready solenoid 546 turns out the ready light 538 in line 409, de-energizes the cycle on solenoid 582 in line 414, de-energizes the advance heads solenoid 580 in line 425, and de-energizes the advance solenoid 590 in line 442.

As previously described, clamping of a workpiece in a workholder energizes clamped solenoid 576 in line 421 which effects energization of the transfer return solenoid 584 in line 423. Solenoid 584 closes transfer return switches 584-1 and 584-2 in line 437, FIG. 39, to energize transverse return valve solenoid 606 which channels fluid pressurized by the motor 502 to effect a return of the transfer bar to its normal position after having loaded a workpiece into a position in which it was automatically clamped as described.

Thus the transverse return valve solenoid 606 operates to return the transfer bar to its initial position while the machining unit heads are being advanced in response to previously described energization of the unit advancing solenoids 594 and 598, line 455 and 471. In this connection it is noteworthy that energization of the unit number one advancing solenoid 594 is continued through relay switch 594-3, line 456, and unit number one returned switch 602, line 459, which remains closed until the slide assembly 12 of unit number one is advanced away from its starting position. In like manner, unit number two advancing solenoid 598 in line 471 has its

energization continued through switch 598-2 in line 472 and unit number two return switch 604 in line 475.

Energization of unit number one advance solenoid 594 closes switch 594-3 in line 458 to energize unlatch solenoid 608 of a mechanically held relay 610 to unlatch this relay. The relay 610 is mechanically held in unlatched position until the slide assembly 12 of unit number one reaches its forward position as will presently appear. Similarly, switch 598-3 in line 474 energizes unlatch coil 612 to shift to unlatched position the mechanically held unlatching switch 614 for the number two unit.

Each of the self-contained machining units 10 is controlled by mechanical cams 244, FIG. 1, and its cam actuated master valve control means 186, FIG. 14, to slow to feeding speed, to return from its forward position at a rapid traverse speed toward its starting position, and to stop at its fully returned or starting position as described.

When the machining units number one and two reach their respective forward positions, forward limit switches 616 and 618 in lines 457 and 473 close to energize respectively latch solenoids 620 and 622 which shift the mechanically held relays 610 and 614 to latched position.

Energization of latch solenoids 620, 622 also closes switches 620-1 and 622-1 in lines 460 and 476 to respectively energize unit forward solenoids 624 and 626 through normally closed unit ready solenoid switches 540-3 and 542-3 respectively.

When energized, the unit number one and two forward solenoids 624 and 626 close switches 624-1 and 624-2 in lines 464 and 480 to energize signal lights 628 and 630 indicating that the respective units number one and two have completed their respective machining operations.

Upon return of machining unit number one to its starting position, the previously mentioned limit switch 602, line 459, is closed to energize the number one ready solenoid 540 through the closed latch solenoid switch 620-2.

In like manner, return of the number two unit to its starting position closes the switch 604 in line 475 to energize the number two ready solenoid 542 through latch solenoid switch 622-2.

Ready solenoid switches 540-1 and 542-1 energize the station ready solenoid 544 in line 447 as previously mentioned and ready solenoid switches 540-4 and 542-4 and in lines 463 and 479 energize signal lights 630 and 632 to indicate that both machining units are ready for the next machining cycle.

As previously mentioned, station ready solenoid 544, line 447, closes switch 544-1 in line 448 to energize section ready solenoid 546, line 408, which closes switch 546-7 in line 429 to energize the unclamp solenoid 562 through normally closed unclamped solenoid switch 636-1, normally closed cycle on switch 582-2, closed transfer return switch 586-2, and automatic solenoid switch 552-6.

When energized unclamp solenoid 562 closes switches 562-3 and 562-4 in line 439, FIG. 39 to energize unclamping valve actuating solenoid 538 to direct fluid to the unclamping end of the work clamping cylinder (not shown) to release the workpiece.

Movement of the workpiece clamp structure to its fully released position actuates a clamp limit switch 640 to energize unclamped solenoid 556 which closes a switch 556-2 in line 432 to energize unclamped signal light 642.

Unclamped solenoid 556 also opens unclamped solenoid switch 556-1 in line 412. This opening of the unclamped switch 556-1 in line 412 will operate to de-energize the automatic solenoid 552 in line 410 and stop the machining section unless another workpiece is properly placed on its unloading station to close a limit switch 644 in line 413 to continue energization of the automatic solenoid 552. Continued energization of the automatic solenoid 552 causes the machining section to continue its machining cycles to the end that machining continues

automatically so long as workpieces are properly supplied successively to the loading station.

In the event machining stops due to the lack of a properly positioned workpiece on a loading station, machining cycles can again be restarted, after a workpiece is properly placed in the loading station by again closing the cycle switch 550 in line 410.

Provision is made for effecting an emergency return of all of the machining units 10 to their starting position. Thus, upon closing of an emergency switch 648 in line 433, an emergency switch solenoid 650 is energized to close emergency return switch 650-1 in line 434, which is connected through a conductor 652 to energize the station emergency solenoid 592 in line 444. This effects a closing of station emergency switch 592-1 in line 461 and station emergency return switch 592-2 in line 477 to energize a unit number one return solenoid 660 and unit number two return solenoid 662 through normally closed ready solenoid switches 540-5 and 542-5 respectively.

Unit number one solenoid 660 closes emergency return switches 660-1 and 660-2 in line 482, FIG. 40 to energize the solenoid actuator 204 to shift the pilot valve 192, FIGS. 13 and 14, to effect an immediate rapid traverse return of the slide assembly 12 of the number one machining unit. Similarly, energization of the unit number two return solenoid 662, line 477, closes return switches 662-1 and 662-2 in line 484 to energize emergency return solenoid 204a to effect an emergency quick return of the slide assembly of the number two machining unit.

As previously mentioned, it is desirable in some situations to slow the feeding rate, as in a drilling operation, before the slide assembly 12 reaches its extreme forward position. For this purpose, the dog 255 is positioned on the support 112, FIG. 1, to actuate the switch 257 when the slide assembly 12 has reached the point where the feeding rate is to be slowed. Operation of the switch 257 energizes the solenoid 173, FIG. 9, to open the pilot valve 171 to supply fluid under pressure to the cylinder 172 and slow the feeding rate as described.

Other switches incorporated into the control structure provide for manual control of the apparatus when it is set for either manual or semi-automatic operation by the selector switch 548, line 412, and the selector switches 531 and 535 in lines 455 and 471.

Manual switch 534 in line 406 provides for starting the fixture motor 532 independently of energization of the section solenoid 522. Manual switch 670 in line 415 provides for energization of the transfer forward solenoid 558 when the machinery is not operating automatically. Similarly, manual switch 672 in line 419 provides for manual energization of the clamp coil 560. In like manner manual switch 674 in line 423 provides for energization of the transfer return solenoid 584. Push button switch 676 in line 425 provides for energization of the advance heads solenoid 580 when the automatic switch 552-4 is open. Push button switch 678 in line 429 provides for manual energization of the unclamp solenoid 562.

When the selector switch 531 in line 452 is set to a manual position, closing of push button switch 680 energizes the motor control solenoid 529 of the number one machining unit through stop switch 682. Energization of the motor control solenoid 529 is continued around the switch 680 by the motor control solenoid switch 529-2. Similar switch controls are provided in line 468 for the manual control of the driving motor for machining unit number two.

Other controls for machining unit number one, which are duplicated for machining unit number two, include a push button switch 684 in line 455 for energizing the unit number one advancing solenoid 594 when the selector switch 531 is set for manual operation. Push button switch 686 in line 462 provides for manual energization of the unit number one return solenoid 660.

The control apparatus illustrated diagrammatically in FIGS. 36, 37, 39, 40 and 41 operates at a relatively low voltage obtained through the step-down transformer 510, FIG. 38. This voltage is not sufficiently high to be dangerous to personnel.

The electrical control structure is actually constructed and assembled in sub-units or sub-assemblies which provide for servicing of the control apparatus in a very efficient manner which virtually eliminates down time of the controlled machining apparatus, which might otherwise be occasioned by necessary servicing of the control apparatus.

Servicing of the control structure is accomplished by the simple expedient of replacing one or more sub-assemblies of the overall control with a new or previously serviced sub-assembly, an operation that can be accomplished with substantially no loss of machining time. A control sub-assembly removed in this manner can be serviced to great advantage in the control maintenance shop where complete service facilities are ready at hand.

As a matter of fact, sub-assemblies of the control apparatus can be changed by relatively unskilled personnel, making it unnecessary to have skilled control service personnel continuously available on short notice.

The relatively high voltage lines 508, FIG. 38, and the related electrical equipment used in energizing the fixture motor 502 and the machining unit motors 24, 24a are isolated from the low voltage control structure to protect those servicing the control structure from coming in contact with dangerously high voltages. Access to this high voltage power equipment is provided only to qualified electricians who need not be on hand when the control apparatus is serviced on the job as described.

A modified pair of coacting gears provided by my invention for transmitting power from the power shaft 35 to the perpendicular drive shaft 52 is illustrated in FIGS. 42 to 47.

The modified gear 700, FIG. 42 keyed to the drive shaft (here designated by the numeral 52a) is a cylindrical gear defining on its periphery a circumferential series of gear teeth 702 of helical form. The gear 700 meshes with and is driven by a driving gear 704 mounted on the power shaft (not shown). A circumferential series of gear teeth 706 formed on the periphery of the gear 704 have a rather complex shape, changing progressively along the length of each gear tooth as shown in FIGS. 45 and 46, which provides effective contact between the teeth 706 and the helical teeth 702 over an extensive zone of mutual engagement of the gears 700 and 704 which extends laterally across a wide face of the gear 704 and longitudinally along an extensive axial length of the gear 700 even though the gear 700 has an unvarying overall diameter along its entire length. Thus, as shown, the circumferential face of the gear 704 has a width, FIG. 43, which is approximately equal to two-thirds of the diameter of the gear 700. Moreover, the helical teeth 702 on the gear 700 make contact with the teeth 706 along a length of the gear 700 approximately equal to the width of the face of the gear 704.

This extensive contact between the teeth 706 on the gear 704 and the coacting helical teeth 702 is obtained by shaping the teeth 704 to have the form illustrated in FIGS. 42 to 47.

As shown in FIG. 45, each gear tooth 706 extends radially outward to a curved tip surface 708, which has an axis of curvature coinciding with the axis of the gear 704. This tip surface extends straight across the projecting end of the gear tooth 706, except as it is centrally relieved by a shallow arcuate relief 710 as shown in FIGS. 44 and 45.

The height of each tooth 706 is relatively short at the opposite longitudinal ends of the tooth and progressively increases in radial depth toward the center of the tooth as shown in FIGS. 45 and 46. The base 712 of each tooth

75

706 is generally uniform in width from end to end of the tooth.

However, the width of the projecting end or tip 708 of each tooth 706 progressively increases from the center 5 of the tooth, where the tip surface 708 of the tooth has a circumferential width which is only approximately one-fourth that of the base of the tooth, toward the longitudinal ends of the tooth where the circumferential width of the radially outer extremity of the tooth is only slightly less than the width of the base of the tooth.

Each tooth 706 has a generally diagonal orientation of the face of the gear 704, which is curved to conform to and intermesh with the helical teeth 702 on the gear 700. Moreover, the general shape of each tooth 706 as viewed in transverse section, has an attitude relative to a radial line from the axis of the gear 704 which changes progressively from the center of the tooth toward opposite longitudinal ends of the tooth.

Thus, as shown in FIG. 47 which shows different longitudinal spaced sections of successive teeth 706, the transverse shape of each tooth is inclined circumferentially forward at one longitudinal end of the tooth. This shape changes progressively along the tooth to a similar but rearward inclination at the other longitudinal end of the tooth.

The opposite faces 714 of each tooth 706 are shaped as shown to make the desired contact with the helical gear teeth 702 extending across the face of the gear 704 and longitudinally along the gear 700.

It will be understood that my invention is not necessarily limited to the particular embodiments illustrated but includes structural variants within the spirit and scope of the invention as defined by the appended claims.

The invention is claimed as follows:

1. A machining unit comprising, in combination a movable machining assembly, means for supporting said assembly for movement relative to a workpiece, a hydraulic actuating cylinder for moving said assembly, a high volume rapid traverse pump, a positive displacement feed pump, valve means for connecting said pumps to operate said cylinder and including a master valve having a plurality of positions including a feeding position, said valve means including a slave valve having a plurality of positions including a feeding position, control means for said slave valve hydraulically interconnected with said master valve to locate the slave valve in the feeding position thereof as an incident to movement of the master valve into the feeding position thereof, hydraulic control means associated with said slave valve to effect upon movement of the latter into said feeding position thereof connections between the intake and outlet of said feed pump and hydraulically opposite sides of said hydraulic motor, and means interconnecting said feed pump with said slave valve to unload the back pressure on the feed pump when the slave valve is in a position other than said feeding position thereof.

2. In a machine tool unit, the combination of a machining assembly, means supporting said assembly for movement, a hydraulic motor connected to move said assembly, a relatively high volume traverse pump, a relatively low volume feed pump, a normally open modulator valve normally connecting the outlet of said traverse pump to exhaust, control valve means for connecting said traverse pump and said feed pump selectively to said hydraulic motor, means controlled as an incident to operation of said valve means and coacting with said modulator valve to close the latter only when the traversing pump is connected through said valve means to operate said motor, a hydraulically actuated lubricant pump having an expandable actuating chamber therein connected to the outlet of said traversing pump, and said lubricant pump including means tending to compress said actuating chamber thereof to effect operation of the lubricant pump as an incident to opening and closing of said modulator valve.

3. In a machine tool unit, the combination of a movable machining assembly, means supporting said assembly for movement, hydraulic motor means for moving said assembly, a relatively high volume traversing pump, a relatively low volume feeding pump, a very low volume pilot pump, a normally open modulator valve normally connecting the outlet of said traversing pump to exhaust, a check valve having an upstream side connected to the outlet of said traversing pump and having a downstream side connected to the outlet of said pilot pump, valve means for controlling operation of said motor means by fluid supplied from said traversing pump and from said feed pump, means connecting the downstream side of said check valve to said valve means whereby an uninterrupted supply of fluid under pressure is provided to said valve means independently of said modulator valve, said valve means including a master valve and including a slave valve controlled hydraulically by said master valve by fluid supplied to said master valve from the downstream side of said check valve, said master valve having a plurality of operating positions therefor including positions which effect connections of said traversing pump to said motor means, and means for closing said modulator valve as an incident to shifting of said master valve means to said last mentioned positions thereof.

4. In a machining unit, the combination of a machining assembly, means supporting said assembly for movement, a hydraulic motor for moving said assembly, a traversing pump, a normally open modulator valve normally connecting said traversing pump to exhaust to eliminate back pressure thereon, a hydraulic modulator valve control responsive to the supply of fluid under pressure thereon to close the modulator valve, a feed pump, valve means for controlling operation of said hydraulic motor by fluid supplied from said traversing pump and from said feed pump, a pilot pump connected to supply fluid to said valve means when said modulator valve is open, said valve means including a multiple position master valve element and a slave valve element controlled hydraulically by the master valve element, means connecting said slave valve element to control operation of said motor by fluid from said feed pump, said master valve element including hydraulic pilot structure connected to said modulator valve control to supply fluid under pressure thereto only when said master valve element is positioned to connect said traversing pump to said motor, means interconnecting said slave valve element hydraulically with said feed pump to normally free the latter from operation against back pressure, and said master valve element including hydraulic pilot structure connected to direct control fluid to actuate said slave valve element in accordance with the position of the master valve.

5. In a self-contained machine tool unit, the combination of a movable machine assembly, means supporting said assembly for movement, a hydraulic motor for moving said assembly, a relatively high volume traversing pump, a relatively low volume feed pump, a pilot pump, valve means for selectively connecting said traversing pump and said feed pump to said motor to energize the latter, a modulator valve normally connecting said traversing pump to exhaust to eliminate back pressure thereon, means operable to close said modulator valve as an incident to operation of said valve means to direct fluid from said traversing pump to said motor, means connecting said pilot pump to said valve means to supply control fluid thereto while said modulator valve is open, and means for connecting said pilot valve to exhaust and at the same time maintaining a limited back pressure of the pilot valve while said modulator valve is open, said last mentioned means comprising means defining an exhaust orifice communicating with the outlet of said pilot pump, and a throttling element biased in a direction to constrict said orifice against the outlet pressure of said pilot valve.

6. In a self-contained machine tool unit, the com-

bination of a self-powered slide assembly, way means supporting said slide assembly for translation, a hydraulic motor connected to translate said slide assembly, a traversing pump, a feed pump, a pilot pump, valve means for connecting said traversing pump and said feed pump selectively to said motor; said valve means including a master valve element having a rapid traverse forward position, a feeding position, a traverse return position, and a neutral position; a modulator valve normally unloading back pressure of said traverse pump, hydraulic means controlled by said master valve and activated when the latter is in either of said traverse positions to close said modulator valve, said master valve element including means therein defining a fluid escape orifice connected to the outlet of said pilot valve when said master valve is in either said neutral or said feeding positions, said escape orifice defining means including throttling means biased to constrict said escape orifice against the back pressure of said pilot pump to maintain a limited pressure thereon to provide a supply of control fluid under pressure to said valve means.

7. In a self-contained machine tool unit, the combination of a translatable machine assembly, a hydraulic motor for translating said assembly, a high volume traverse pump for supply fluid under pressure to operate said motor at a rapid traverse speed, a relatively low volume feed pump for supplying a fluid under pressure to operate said motor at a feeding speed, a low volume pilot pump, means continuously driving all three of said pumps, a normally open modulator valve normally connecting the output of said traverse pump to exhaust to eliminate back pressure thereon, said modulator valve having a hydraulic control therefor responsive to the application of pilot pressure thereto to close the modulator valve, a hydraulically actuated lubricant pump having an expansible actuating means connected to the outlet of said traversing pump to effect operation of the lubricant pump as an incident to the increase and decrease of back pressure on the traversing pump upon closing and opening said modulator valve, shiftable control valve means for connecting said traverse pump and said feed pump selectively to said motor to controllably translate said assembly at rapid traverse and feeding speeds, said valve means including means normally connecting said feed pump to exhaust, and said valve means including pilot valve means for directing fluid under pressure from said pilot pump to said hydraulic control for said modulator valve to close said modulator valve as an incident to operating of said valve means to direct operating fluid from said traverse pump to said hydraulic motor.

8. In a self-contained machine tool unit, the combination of a movable machine assembly, a hydraulic motor for translating said assembly, a relatively high volume traverse pump for supplying fluid under pressure to operate said motor at a rapid traverse speed, a relatively low volume feed pump for supplying fluid under pressure to operate said motor at a feeding speed, valve means interconnected with said traverse pump and said feed pump to normally unload both of said pumps to eliminate back pressure thereon, said valve means including hydraulically actuated means for connecting said traverse pump and said feed pump selectively to said motor to effect translation thereof at translating speeds and feeding speeds, a hydraulically actuated lubricant pump including expansible actuating means connected to the outlet of one of said traverse and feed pumps to effect operation of said lubricant pump as an incident to the changing of the back pressure on said one pump, a very low output pilot pump, means for limiting the back pressure on said pilot pump to a low value, and means interconnecting said pilot pump with said valve means to effect hydraulic operation of the latter when the back pressure is unloaded from said traverse pump and said feed pump.

9. In a machine tool unit, the combination of a mov-

able machine assembly, a hydraulic motor for translating said assembly, a relatively high volume traverse pump for supplying fluid under pressure to operate said motor at a rapid traverse speed, a relatively low volume feed pump for supplying fluid under pressure to operate said motor at a feeding speed; hydraulically controlled valve means interconnected between both of said pumps and said motor and including a hydraulically operated control member having a rapid traverse forward position, a feeding position, a rapid traverse return position and a neutral position; said valve means including means for unloading said rapid traverse pump of back pressure when said control member is in either said feeding position or said neutral position and including means for connecting said rapid traverse pump to said motor when said control member is in either of said rapid traverse positions, said valve means including means for connecting said feed pump to said motor when said control member is in said feeding position, said valve means including means for completely unloading back pressure from said feed pump when said control member is in any one of said positions other than said feeding position, a low output pilot pump, means for limiting the output pressure of said pilot pump, and means connecting said pilot pump to operate said valve means when said traverse pump and said feed pump are unloaded.

10. In a machine tool unit, the combination of a movable machine assembly, a hydraulic motor for translating said assembly, a relatively high volume traverse pump for supplying fluid under pressure to operate said motor at a rapid traverse speed, a relatively low volume feed pump for supplying fluid under pressure to operate said motor at a feeding speed, valve control means for connecting said traverse and feed pumps selectively to said motor to energize the latter; said valve control means including a master valve element having a rapid traverse forward position, a feeding position, a rapid traverse return position, and a neutral position; said valve control means including first valve means coacting with said traverse pump normally to unload the latter, said valve control means including second valve means coacting with said feed pump normally to unload the latter, first hydraulic actuating means coacting with said first valve means to control the latter and being controlled by port means controlled by said master valve element to condition said traverse pump for supplying operating fluid through said valve control means to said motor upon movement of the master valve element to either of said traverse positions thereof, second hydraulic actuating means coacting with said second valve means to control the latter and being controlled by port means controlled by said master valve element to condition said feed pump to supply actuating fluid through said valve control means to said motor upon movement of said master valve element to said feeding position thereof, third hydraulic actuating means coacting with said master valve element to move the latter from one position to another, means for supplying actuating fluid under pressure for operating said third hydraulic actuating means, and solenoid operated pilot valve means connected to control said third hydraulic actuating means.

11. In a machine tool unit, the combination of a movable machine assembly, a hydraulic motor for moving said assembly, a high volume pump for supplying fluid under pressure to operate said motor at a relatively high speed, a low volume feed pump for supplying fluid under pressure to operate said motor at a relatively low speed, valve control means interconnected between said pumps and said motor to supply operating fluid to said motor from said pumps selectively; said valve control means including a valve element having a high speed position, a low position, and a neutral position; said valve control means including first valve means hydraulically controlled by said valve element and coacting with said high volume pump normally to unload the latter and being responsive to

movement of said valve element to said high speed position thereof to effect the supply of fluid under pressure from said high volume pump to said motor, said valve control means including second valve means hydraulically controlled by said valve element and coacting with said low volume pump normally to unload the latter and being responsive to movement of said valve element to said low speed position thereof to effect the supply of fluid under pressure from said low volume pump to said motor, and means for moving said valve element to different positions thereof.

12. In a machine tool unit, the combination of a movable machine assembly, a hydraulic motor for translating said assembly, a relatively high volume traverse pump for supplying fluid under pressure to operate said motor at a rapid traverse speed, a relatively low volume feed pump for supplying fluid under pressure to operate said motor at a feeding speed, valve control means for connecting said traverse and feed pumps selectively to said motor to energize the latter; said valve control means including a master valve element having a rapid traverse position, a feeding position, and a neutral position; said valve control means including first valve means coacting with said traverse pump normally to unload the latter, said valve control means including second valve means coacting with said feed pump normally to unload the latter, first hydraulic actuating means coacting with said first valve means to control the latter and being controlled by said master valve element to condition said traverse pump for supplying operating fluid through said valve control means to said motor upon movement of the master valve element to said traverse position thereof, second hydraulic actuating means coacting with said second valve means to control the latter and being controlled by said master valve element to condition said feed pump to supply actuating fluid through said valve control means to said motor upon movement of said master valve element to said feeding position thereof, and means for moving said master valve element to different positions thereof.

13. In a machine tool unit, the combination of a movable machine assembly, a hydraulic motor for translating said assembly, a relatively high volume traverse pump for supplying fluid under pressure to operate said motor at a rapid traverse speed, a relatively low volume feed pump for supplying fluid under pressure to operate said motor at a feeding speed, valve control means for connecting said pumps selectively to said motor to energize the latter; said valve control means including a master valve element having a plurality of positions which include a neutral position, a feeding position, and a rapid traverse position; said valve control means including first valve means coacting with said traverse pump normally to obviate subjection of the traverse pump to back pressure, said valve control means including second valve means coacting with said feed pump normally to obviate subjection of the feed pump to back pressure, first hydraulic actuating means controlled by control ports controlled by said master valve element and coacting with said first valve means to condition said traverse pump to supply operating fluid through said valve control means to said motor upon movement of said master valve element to said traverse position thereof, second hydraulic actuating means controlled by control ports controlled by said master valve element and coacting with said second valve means to condition said feed pump to supply operating fluid through the valve control means to said motor upon movement of said master valve element to said feeding position thereof, and means for supplying to said valve control means when said master valve element is in said neutral position thereof operating fluid under pressure for operating either of said hydraulic actuating means.

14. In a machine tool unit, the combination of a movable machine assembly, a hydraulic motor for translating said assembly in opposite directions, pump means for supplying fluid under pressure to operate said motor;

valve control means connected between said pump means and said motor to control operation of the latter and including a valve element having a neutral position, an advancing position which effects operation of said motor to advance said assembly, and a return position which effects operation of said motor to retract said assembly; settable means coacting with said valve element to shift the latter from said advancing position thereof to said neutral position thereof as an incident to movement of said assembly to a predetermined position, hydraulic actuating means coacting with said valve element for moving the latter to said return position thereof, a pilot valve, means for supplying fluid under pressure to said pilot valve, a restricted flow channel connecting said pilot valve with said actuating means and including flow restriction means which limits fluid flow from the pilot valve to the actuating means, a mechanical actuator for shifting said pilot valve to a dwell position as an incident to movement of said assembly to said predetermined position thereof, said pilot valve being operable in said dwell position thereof to supply operating fluid through said restricted flow channel to said actuating means to effect gradual movement of said valve element toward said return position thereof, means defining a substantially unrestricted flow passage positioned to be supplied with fluid under pressure from said pilot valve when the latter is in said dwell position thereof, said flow passage extending to a port positioned to be blocked by said valve element when the latter is moved to said feeding position thereof by said mechanical actuator and unblocked as an incident to progressive movement of said valve element toward return position thereof to communicate with and supply additional fluid to said actuator means to speed up movement of said valve element to said return position thereof, means defining a free flow channel extending from said pilot valve to said actuating means, means for shifting said pilot valve to a rapid return position, and said pilot valve including means responsive to shifting of the pilot valve to said return position thereof to supply fluid through said free flow channel to said actuating means to effect quick movement of said valve element to said return position thereof.

15. A self-contained machine tool unit comprising, in combination, a self-powered slide assembly, way means supporting said slide assembly for translation, a hydraulic motor for translating said slide assembly, a relatively high volume traverse pump for supplying fluid under pressure to operate said motor at a rapid traverse speed, a relatively low volume feed pump for supplying fluid under pressure to operate said motor at a feeding speed; valve control means interconnected between both of said pumps and said motor and including a control member having a rapid traverse forward position, a feeding position, a rapid traverse return position, and a neutral position; said valve means including means responsive to movement of said control member into either said feeding position or said neutral position to unload said rapid traverse pump and responsive to movement of said control member into either of said rapid traverse positions to supply fluid under pressure to said motor from said traverse pump, said valve means including means responsive to movement of said control member to said feeding position thereof to supply fluid under pressure to said motor from said feed pump and responsive to movement of said control member to any of said positions thereof other than said feeding position to unload said feed pump, and means for moving said control member to said various positions thereof.

16. In a machine tool unit, the combination of a movable machine assembly, a hydraulic motor for translating said assembly in opposite directions, pump means for supplying fluid under pressure to operate said motor; valve control means connected between said pump means and said motor to control operation of the latter and including a valve element having a neutral position, an advancing

position which effects operation of said motor to advance said assembly, and a return position which effects operation of said motor to retract said assembly; means for terminating advancing movement of said assembly in a predetermined position, hydraulic actuating means coacting with said valve element to move the latter to said return position thereof, a pilot valve, means for supplying fluid under pressure to said pilot valve, a restricted flow channel connecting said pilot valve with said actuating means, a free flow channel connecting said pilot valve to said actuating means, means for moving said pilot valve to a dwell position thereof as an incident to movement of said assembly to said predetermined position thereof, said pilot valve being operable in said dwell position thereof to supply operating fluid through said restricted channel to said actuating means to effect gradual movement of said valve element toward said return position thereof, means for moving said pilot valve to a rapid return position thereof, and said pilot valve including means operable in said rapid return position of the pilot valve to supply fluid through said free flow channel to said actuator to effect quick movement of said valve element to said return position thereof.

17. In a machine tool, the combination of a movable machine assembly, a hydraulic motor for translating said assembly, a translating pump for supplying fluid under pressure to operate said motor, valve control means connected between said pump and said motor to control the latter, a modulator valve connected to the output side of said pump and including a valve seat facing in a downstream direction, a valve cylinder disposed in alignment with said seat on the downstream side thereof and having a transverse sectional area substantially larger than the area encircled by said seat, a valve plunger slidably fitted into said cylinder in opposing relation to said seat for movement into closing engagement therewith and forming a seal between said seat and the opposite end of said cylinder, means connecting the downstream side of said valve seat to exhaust, a second pump operable to provide a continuous supply of pilot fluid under pressure, a check valve having an upstream side connected to the outlet of said translating pump and having a downstream side connected to the outlet of said second pump, said valve control means including component valve means connected to the downstream side of said check valve and to said opposite end of said valve cylinder normally to connect said opposite end of said valve cylinder to exhaust and to connect the downstream side of said check valve to said opposite end of said cylinder to move said plunger into engagement with said seat as an incident to operation of said valve control means to connect said translating pump to said motor.

18. In a machine tool, the combination of a movable machine assembly, a double acting hydraulic translating cylinder having a piston rod projecting from one end thereof and connected to translate said assembly, a traversing pump, a feed pump; valve control means connected between said pumps and said motor and including a valve control element having a traverse forward position, a feeding position, a traverse return position, and a neutral position; said valve control means including means responsive to movement of said valve control element to any of said positions thereof other than said traverse positions thereof to unload said traversing pump and responsive to movement of said valve control element to either of said traverse positions thereof to connect said traversing pump to supply operating fluid to said translating cylinder, said valve control means including means responsive to movement of said valve control element to any position thereof other than said feeding position thereof to unload said feed pump and responsive to movement of said valve control element to said feeding position thereof to connect the intake of said feed pump to the piston rod end of said cylinder and to connect the outlet of said feed pump to the opposite end of said cylinder

to supply fluid under pressure thereto, and means for supplying make-up fluid to the intake of said feed pump when said valve control element is in said feeding position thereof.

19. In a machine tool, the combination of a movable machine assembly, a double acting hydraulic translating cylinder connected to translate said assembly, a traversing pump, a feed pump; valve control means connected between said pumps and said cylinder and including a valve control element having a traverse position, a feeding position, and a neutral position; means for operating said valve control element, said valve control means including first means coacting with said traversing pump normally to unload the latter, said first means being hydraulically controlled by said valve control element to respond to movement of said valve control element to said traverse position thereof to connect said traversing pump to supply operating fluid to said cylinder, and said valve control means including second means coacting with said feed pump normally to unload the latter, said second means being hydraulically controlled by said valve control element to respond to movement of said control element to said feeding position thereof to connect the intake and the outlet of said feed pump to opposite ends of said cylinder to energize the latter to translate said assembly.

20. A machine tool unit comprising, in combination, a self-powered slide assembly, a base supporting said slide assembly for translation, a hydraulic motor connected to translate said assembly, said assembly including a housing defining therein a transmission chamber, a power shaft extending across said chamber, a drive shaft extending across said chamber in generally perpendicular relation to said power shaft, gears connecting said power shaft to said drive shaft, said transmission chamber being formed to define a lubricant reservoir in the lower portion thereof, said housing defining an overflow opening from said lubricant reservoir located at a level somewhat above the lowermost portion of the lowest one of said gears, an electric motor connected to energize said power shaft, a feed pump connected to one end of said drive shaft, a traversing pump connected to the other end of said drive shaft; hydraulically controlled valve means interconnected between said pumps and said hydraulic motor and including a control member having a rapid traverse forward position, a feeding position, a rapid traverse return position, and a neutral position; hydraulic operating means for moving said control member, said valve means including means which is responsive to movement of said control member to either of said traverse positions to connect said traversing pump to supply operating fluid to said hydraulic motor and which is responsive to movement of said control member to any of said positions other than said traverse positions thereof to unload said traversing pump, said valve means including means which is responsive to movement of said control member to said feeding position thereof to connect said feed pump to said hydraulic motor to supply operating fluid under pressure to the latter and which is responsive to movement of said control member to any of said positions other than said feeding position to unload said feed pump, and means for supplying operating fluid under pressure when said control member is in said neutral position to said hydraulic operating means for said control member.

21. A machine tool unit comprising, in combination, a movable machine assembly, a hydraulic motor connected to move said assembly, a low volume feed pump, a high volume traversing pump, means for continuously energizing both said pumps; hydraulically controlled valve means interconnected between said pumps and said motor and including a control member having a rapid traverse forward position, a feeding position, a rapid traverse return position and a neutral position; hydraulic operating means for moving said control member, said valve means including means which normally unloads said traversing pump and which is responsive to movement of said con-

trol member to either of said traverse positions to connect said traversing pump to supply operating fluid to said motor, said valve means including means which normally unloads said feed pump and which is responsive to movement of said control member to said feeding position thereof to connect said feed pump to said motor to supply operating fluid under pressure to the latter, and means for supplying operating fluid under pressure when said control member is in said neutral position to said hydraulic operating means for said control member.

22. In a machine tool, the combination of a movable machine assembly, a hydraulic motor connected to move said assembly, a traversing pump, a feed pump; valve control means connected between said pumps and said motor and including a valve control element having a traverse position, a feeding position, and a neutral position; means for operating said valve control element, said valve control means including first means coacting with said traversing pump normally to unload the latter, said first means being hydraulically controlled by said valve control element to respond to movement of said valve control element to said traverse position thereof to supply operating fluid under pressure to said motor from said traversing pump, said valve control means including second means coacting with said feed pump normally to unload the latter, and said second means being hydraulically controlled by said valve control element to respond to movement of said control element to said feeding position thereof to supply operating fluid under pressure to said motor from said feed pump.

23. In a machine tool unit, the combination of a movable machine assembly, a hydraulic motor for translating said assembly in opposite directions, a relatively high volume traverse pump for supplying fluid under pressure to operate said motor at a rapid traverse speed, a relatively low volume feed pump for supplying fluid under pressure to operate said motor at a feeding speed, hydraulically operated pump adjusting means coacting with said feed pump to controllably reduce the output thereof, valve control means connected between said pumps and said motor for connecting said pumps selectively to said motor to energize the latter; said valve control means including a master valve element having a plurality of positions which include a rapid traverse forward position, a feeding position, a rapid traverse return position, and a neutral position; said valve control means including first valve means hydraulically controlled by said master valve element and coacting with said traverse pump normally to unload the latter and being responsive to movement of said master valve element to either of said traverse positions thereof to effect the supply of fluid under pressure from said traverse pump to said motor, said valve control means including second valve means hydraulically controlled by said master valve element and coacting with said feed pump normally to unload the latter and being responsive to movement of said valve element to said feeding position thereof to effect the supply of fluid under pressure from said feed pump to said motor, settable control means positioned for operation by advancing movement of said machine assembly and coacting with said hydraulically operated pump adjusting means to reduce the output rate of said feed pump as an incident to advancement of said machine assembly to a first predetermined position, means for terminating advancing movement of said machine assembly in a second predetermined position, hydraulic actuating means coacting with said master valve element to move the latter to said traverse return position thereof, a pilot valve means for supplying fluid under pressure to said pilot valve, a restricted flow channel connecting said pilot valve to said hydraulic actuating means, means for moving said pilot valve to a dwell position thereof as an incident to movement of said machine assembly to said second predetermined position thereof, and said pilot valve being operable in said dwell position thereof to supply operating fluid through said restricted flow channel to said actuating means to effect

31

gradual movement of said master valve element toward
said traverse return position thereof.
